Inventor

UNITED STATES PATENT OFFICE.

DAVID B. GALBALLY, OF NEW YORK, N. Y., ASSIGNOR TO THE UNIVERSAL STEEL PACKAGE CO., OF DOVER, DELAWARE, A CORPORATION OF DELAWARE.

MACHINE FOR APPLYING BINDING-WIRE.

1,240,042.

Specification of Letters Patent. Patented Sept. 11, 1917.

Application filed July 28, 1915. Serial No. 42,394.

To all whom it may concern:

Be it known that I, DAVID B. GALBALLY, a citizen of the United States, residing at New York, in the county of New York and State of New York, have invented certain new and useful Improvements in Machines for Applying Binding-Wire; and I do hereby declare the following to be a full, clear, and exact description of the invention, such as will enable others skilled in the art to which it appertains to make and use the same:

My invention relates to means for applying a binding wire to any object which it is desirable to secure with a wire binding; and while my improved device may be used for many purposes, I have shown it with special reference to its use in applying wire hoops to barrels.

The object of my invention is to provide a device of this character which shall be simple, cheap, and so constructed as to be capable of applying a wire binding under heavy tension to the object to be bound, in a minimum of time and with but a slight effort on the part of the operator.

Referring to the drawings, Figure 1 is a central longitudinal section of my improved binder applying device;

Fig. 2 is a perspective view of my improved device shown in the act of applying a wire binder to a barrel;

Fig. 3 is a side elevation of the nut which operates the pull rod of my device;

Fig. 4 is a section along the lines 4—4 of Fig. 1, looking in the direction of the arrow.

Fig. 5 is a section along the lines 5—5 of Fig. 1, looking in the direction of the arrow.

Fig. 6 is an enlarged perspective view of the end of the pull rod.

10 represents a casing formed of metal and provided with a tapering body 11, terminating at its smaller end in a cylindrical extension or shoulder 12 for a purpose hereinafter described.

The interior of the tapering portion 11 is hollow and is provided with a bearing boss 13; the larger end of the tapering portion 11 is closed by a flange 14 and from the outer edge of this flange extends a cylindrical portion 15.

The tapering portion 11, the shoulder 12, the bearing boss 13, the flange 14 and the cylindrical portion 15 are preferably cast in

one piece but they may be constructed in several pieces if desired.

The cylindrical portion 15 is closed by a cap 16 secured thereto by the screws 17.

The flange 14 and the cap 16 at their centers are provided with cylindrical holes in which are mounted flanged bearing bushings 18 and 19. In said bushings are mounted respectively the cylindrical portions 20 and 21 of the nut shown in Fig. 3. The enlarged portion 22 of said nut extends between the flanges of the bearing bushings 18 and 19 and prevents any motion of said nut.

The nut shown in Fig. 3 is provided with a threaded hole 23 extending through the cylindrical portions 20 and 21 and the enlarged portion 22; this nut is also provided with an arm 24 formed integrally therewith having a hole at its extremity 25, in which is riveted a pin 26 upon which is revolvably mounted a handle 27.

The end 28 of the pull rod is threaded and works freely in the threaded hole 23 of the nut shown in Fig. 3.

Formed integrally with the threaded portion 28 of the pull rod 29 is a cylindrical portion 30 somewhat smaller in diameter than the threaded portion 28. This cylindrical portion 30 is provided with a slot 31 extended to about the position shown in Fig. 1 at 32.

A screw 33 secured to the bearing boss is provided with a point 34 which extends into the slot 31 and thus prevents the pull rod 29 from turning.

The key-way 31 extends only as far as 32 in Fig. 1, in order that the point 34 of the screw 33 may strike the end of the said slot and prevent the screw 28 from passing out of the hole 23.

The outer end of the pull rod 29 is provided with a hole 35 and grooves 36 and 37 are cut from the end of said pull rod to meet said hole 35.

The operation of my improved binder applying device is as follows:

One end of the wire 38 that is to be applied to the barrel is formed into a loop such as 39 by twisting said end around the body of the wire as shown at 40 in Fig. 2.

The loop 39 is then placed over the cylindrical extension 12 of my device and the other end of the wire 38 is then passed around the barrel and through the hole 35

in the end of the pull rod 29 and bent into the grooves 36 and 37 so as to lie below the surface of the portion 30 of the pull rod. The end 41 of the wire 38 is then cut off as shown in Fig. 6.

The operator then holds the casing in the position shown in Fig. 2 and turns the handle 27 in a clock-wise direction. This will cause the thread in the hole 23 of the nut 10 to act upon the thread 28 of the pull rod 29 so as to draw the wire 38 tightly around the barrel.

The wire 38 is left originally of such a length that when the end is passed through 15 the hole 35 of the pull rod 29, and the binding process is completed, the grooves 36 and 37 will have been drawn inside of the cylindrical extension 12, thus carrying the wire 38 through the loop 39.

20 The operator then moves the casing of my binder applying device toward the left from the position shown in Fig. 2 which causes the loop 39 to pass off of the cylindrical extension 12 and allows the loop 39 to engage with the end of the wire 38.

The continued motion of the casing toward the left as just described results in a hook such as 42, shown in Fig. 2, being formed around the loop 39.

30 The handle 27 is then rotated in a counter clockwise direction when the end 41 (see Fig. 6) can be bent up and the wire 38 be removed from the hole 35, shown in Fig. 1.

At this stage of the operation an end 43 35 is left on the hook 42 (see Fig. 2) and the final operation is the cutting of the end 43

from the hook 42 in any approved manner, leaving the hook as shown at 44 in Fig. 2.

Thus it will be seen that by the application of my improved binder applying device 40 I am enabled to put a cheap and strong binder around any article it is desired to bind, and apply any suitable amount of force to said binder and after the same is applied to secure the ends of said binder 45 while the same is under stress.

While I have shown my improved binder applying device as applied to a barrel it may be used for a great variety of purposes and many changes may be made in the construction of my device without departure 50 from the main features thereof.

I claim:—

1. In a binder applying device, the combination of a casing having means for holding one end of a binding wire, with a pull rod having means on one end for holding the other end of said binding wire, means for preventing said pull rod from turning, a nut mounted in bearings in said casing and 60 threaded on the other end of said pull rod, and a handle for turning said nut.

2. In a binder applying device, the combination of a casing having a conical end provided with a cylindrical tip, a cylindrical body adjacent to said conical end, bearings in said cylindrical body, a nut mounted in said bearings, and a pull rod slidably mounted in a bearing in said conical end and threaded into said nut.

In testimony whereof, I affix my signature.

DAVID B. GALBALLY.
